(57) **CLAIM**

The ornamental design for a reversible V groove round nose bit, as shown and described.

DESCRIPTION

FIG. 1 is a perspective view of a reversible V groove round nose bit of the present invention

FIG. 2 is a front view of the reversible V groove round nose bit shown in FIG. 1.

FIG. 3 is a side view of the reversible V groove round nose bit shown in FIG. 1.

FIG. 4 is a top view of the reversible V groove round nose bit shown in FIG. 1; and,

FIG. 5 is a bottom view of the reversible V groove round nose bit shown in FIG. 1.
